(57) **CLAIM**

The ornamental design for a photography tripod as shown and described.

DESCRIPTION

FIG. 1 is a top, front and left side perspective view of a photography tripod showing my new design;

FIG. 2 is a top, rear and left side perspective view thereof; FIG. 3 is a bottom, front and left side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a front elevational view showing the photography tripod in a closed state;

FIG. 11 is an enlarged view of portion 11 in FIG. 1;

FIG. 12 is an enlarged view of portion 12 in FIG. 1;

FIG. 13 is an enlarged view of portion 13 in FIG. 3;

FIG. 14 is an enlarged view of portion 14 in FIG. 3; and,

FIG. 15 is an enlarged view of portion 15 in FIG. 3.

The dash dash lines in FIG. 1, 3, 11, 12, 13, 14, 15 represent a boundary for the purposes of disclosing areas of enlargement and form no part of the claimed design.

1 Claim, 15 Drawing Sheets
